6 Claims. (Cl. 248—45)

1

The present invention relates generally to antennas and more particularly to television antenna supporting devices.

Because of the relatively high frequencies employed in the transmission of television signals, these transmissions are directional and are of relatively limited range. In order to increase the possibility of signal reception, the receiving antenna should be mounted as high as practicable above the earth's surface, and in order to attain maximum signal strengths from several transmitting stations within whose service areas the receiving antenna is located, it is desirable that the receiving antenna be rotatably mounted to the end that it can be properly oriented in the direction of the particular transmitting station whose signal is to be received. A supporting structure for a receiving antenna, therefore, should include provision both for rotating the antenna with respect to some fixed structure, such as a roof top, chimney, or the like, and also the adequate strength to sustain the antenna against the action of winds.

It is a general object of the present invention to provide a novel supporting structure for use between the fixed and rotatable portions of a mast for mounting a conventional television antenna which will accommodate various mast sizes yet is of exceedingly simple character and permits of economical manufacture.

Still another object of the invention is to provide an antenna mast supporting device which is operative to prevent loosening of the mast sections when vibrated under the action of winds and which is operative to maintain coaxial relation between the fixed and movable mast sections regardless of the sizes of the sections.

The objects of the invention thus generally set forth, together with other objects and ancillary advantages, are attained by the construction and arrangement shown by way of illustration in the accompanying drawings, in which:

Figure 1 is a fragmentary perspective view showing a rotary joint structure and supporting means embodying the features of the present invention between fixed and rotatable sections of an antenna mast.

Fig. 2 is a fragmentary side elevation, on a somewhat enlarged scale and partially in section, of a portion of the mast supporting structure illustrated in Fig. 1.

Figs. 3, 4 and 5 are transverse sections taken substantially in the plane of the line 3—3 in Fig. 2.

Fig. 6 is a fragmentary longitudinal section

taken substantially in the plane of the line 6—6 in Fig. 1.

Fig. 7 is a fragmentary transverse section taken substantially in the plane of line 7—7 in Fig. 1.

While the invention is susceptible of various modifications and alternative constructions, there is shown in the drawings and will herein be described in detail the preferred embodiment, but it is to be understood, however, that there is no intention to limit the invention to the form disclosed, but it is intended to cover all modifications and alternative constructions falling within the spirit and scope of the invention as expressed in the appended claims.

15 In accordance with the present invention, there is provided an antenna mast supporting structure for maintaining in upright coaxial relation fixed and rotatable mast sections and embodying means for gripping the mast sections which is capable of accommodating a relatively wide range of mast sizes. The coaxial supporting structure is effective, at the same time, to prevent loosening of the mast sections and to eliminate localized deformation of the mast sections which would result in weakening the same and making them liable to be bent as the antenna is subjected to wind action.

By way of illustration, there is shown in Fig. 1 of the drawings the joining means interposed between a fixed mast section 10 and a relatively rotatable mast section 12. This means includes a housing 15 enclosing an electric motor together with upper and lower clamping portions 18, 20 for mounting the motor housing on the fixed mast section 10 and for mounting the rotatable mast section 12 on the motor housing 15. The motor and associated components disposed within the housing 15 form no part of the present invention. It will suffice to say that the housing 15 rotates with respect to a pillar member 14, the joint between them being sealed by rubber packing 17. For the details of this structure, reference is made to my copending applications Serial Nos. 230,266 and 230,267, filed June 7, 1951, and Serial No. 243,108, filed August 22, 1951, now Pat. 2,668,920.

40 The motor housing 15 is equipped with a coaxially disposed upwardly projecting post 19 which is adapted to be received in the lower end of the mast section 12. In order to accommodate masts of various internal diameters, the post 19 is equipped with a split conical bushing 21 having an axial bore therethrough for the reception of the post. It will be apparent from Fig. 2 of the drawings that masts of rel-

atively small internal diameters will engage the bushing 21 adjacent the top thereof while masts of larger internal diameters will slip further down on the collar.

The rotatable mast 12 is mounted in coaxial relation on the motor housing 15 for rotation therewith by means of the supporting structure portion generally designated 20. The latter, in the present instance, includes an annular supporting member 22 in the form of a contractile band or collar adapted to embrace the motor housing 15, a collar 24 for gripping the rotatable mast 12 together with three equally spaced struts 23 serving to space the members 22 and 24 apart, maintain them in coaxial relation, and to brace the mast 12 against any relative movement with respect to the motor housing 15. As shown, the annular supporting member 22 comprises a split band having outward ears 25 on the free ends thereof. The ears 25 are apertured for the reception of a bolt-and-nut assembly 26 by means of which the band ends are drawn together so as to firmly grip the motor housing 15. In order to prevent disengagement of the member 22 from the motor housing, the latter is preferably provided with a peripheral groove 27 for the reception of the member 22.

Referring particularly to Fig. 3, it will be noted that the collar 24 comprises three segments 28, 29 and 30 each having a central arcuate section for disposition adjacent the mast 12. The central arcuate sections of the collar segments 28, 29 and 30 are curved to correspond to the average diameter of the range of mast sizes to be received therein. The ends of the sections 28, 29 and 30 are turned outwardly and are apertured for the reception of bolt-and-nut fasteners 31.

The struts 23 are fixed at their lower ends to the outer surface of the collar 22 by welding or the like. At their upper ends the struts 23 are rigidly secured to the inner surfaces of the arcuate central sections of the collar segments 28, 29 and 30 and are of arcuate form to conform to the shape of the segments. Intermediate their ends the struts 23 have a longitudinal strengthening rib 32 provided to stiffen the same. It will be noted that the end portions of the struts 23 which are respectively fixed to the collar sections 28, 29 and 30 and to the member 22 lie parallel to the central axis of the whole mast assembly. These end portions are joined with the ribbed intermediate portions of the struts by relatively smooth "bends" as indicated at 33 (Fig. 1), the ribs 32 terminating in spaced relation to the bends.

The supporting structure portion 20 permits accommodation of masts 12 of various sizes. The sections 28, 29 and 30 of the gripping collar 24 may be readily spread apart or moved together simply by adjusting the bolt-and-nut fasteners 31. Upon reference to Fig. 3, it will be seen that the curvature of the intermediate segments of the collar sections 28, 29 and 30 and of the upper ends of the struts 32 is such that the ends of the struts bear against the outer surface of the mast throughout their entire widths for a mast section having an average outer diameter of the range of mast section sizes to be received therebetween. Thus upon tightening the bolt-and-nut fasteners 31, the mast 12 will be uniformly squeezed. This will result, upon continued tightening, in a uniform squeezing of the tubular mast 12.

In Fig. 4 there is shown the instant supporting structure portion 20 applied to a mast section

having an outer diameter smaller than that shown in Fig. 3. It will be apparent in this instance that the ends of the struts 32 bear against the outer surface of the mast in longitudinal line contact, the contact lines being spaced substantially 120° apart, when the fasteners 31 are adjusted so that the inner surfaces of the upper ends of the struts are just brought to bear against the outer mast surface. However, upon tightening the fasteners 31, this line contact is changed into surface or ribbon contact at 23a by the slight uniform deformation of the mast as the clamping pressure increases. Accommodation of the smaller sized mast 12 requires an alteration of the angle of bend at 33 so that the upper ends of the struts 32 extend parallel to the mast so as to obtain full gripping thereof throughout the length of the ends of the struts. Similar adjustment of the angle of the bands 33 is required to accommodate larger sized masts 12.

As shown in Fig. 5, the clamping collar sections 28, 29 and 30 are spread apart to grip a mast of such increased diameter. In view of the fact that the arcuate segments of the collar sections 28, 29 and 30 and the ends of the struts 32 are made of average curvature, in this instance there is line contact between the edges of the ends of the struts with the surface of the mast 12. Again, as the bolt-and-nut fasteners 31 are tightened, there results uniform deformation of the mast due to the uniformly spaced contact areas. As a result of such deformation, the contact is transformed from line contact to a ribbon surface engagement at six areas indicated at 23b.

The above action is an important feature of the present invention. It distinguishes the operation of the instant structure from conventional clamps employing set screw arrangements wherein gripping is dependent upon a localized application of force to the mast. As a result, adequate tightening exceeds the elastic limit and produces a localized deformation which weakens the mast and causes it to loosen when the antenna structure is subjected to wind action. Upon taking up the play, the same loosening at the set screw is repeated regardless of how tight the set screw might be set. Since tightening the set screw exceeded the elastic limit of mast section at its point of contact, there is little or no resilience afforded by the mast to accommodate wind-caused vibration between it and the set screw. As a result the deformation is increased and the mast is again loose.

With the present mast supporting structure, however, the slight uniform deformation, which results from the application of force equally distributed about the mast section with relatively large ribbon area contact between collar and mast, permits adequate tightening to obtain well within the elastic limit of the mast. Furthermore, even if the fasteners 31 be tightened so that the unit area pressure produced causes the mast to take on a small amount of permanent set, this only increases the contact area to at least partially reduce unit area pressure and there results no progressive deforming and resulting loosening.

It is also apparent from the foregoing description that the struts 23 which are reinforced through the provision of the strengthening ribs 32 are stiff for all diameters of masts to be accommodated by the supporting structure. Since bending of the strut end portions to place the

same parallel to the mast axis is localized between the strut end portions and the strengthening ribs, occurring immediately adjacent the collars 22 and 24, the struts provide rigid connecting means acting in both tension and compression as braces between the collars. The present construction thus provides an exceedingly strong arrangement for supporting all mast sizes and in conjunction with the post and bushing 19, 21 serves to maintain the mast section supported therein in exact coaxial relation with the housing 15.

The supporting structure portion 18 whereby the rotary joint is secured to the fixed mast 10 includes a number of the same features as the supporting structure portion 20 above described. Referring particularly to Figs. 1, 6 and 7, it will there be seen that the supporting structure portion 18 includes an annular supporting member 40 rigid with which are the ends of struts 42. The latter, in turn, support mast gripping collars 44 which are identical with the collar 24 of the supporting structure portion 20. The lower ends of the struts are of arcuate form and are made rigid with the intermediate arcuate segments 48, 49 and 50 of the clamping collars 44. These outer strut ends are adapted to engage the outer surface of the fixed mast 10 to grip the same therebetween upon tightening bolt-and-nut fasteners 51. The strut end portions, in this instance, however, are elongated and two of the collars 44 are provided so that adequate purchase on the fixed mast section 10 obtains.

For this portion of the mast supporting structure, the annular supporting member 40 is of inverted cup-shape and is provided with a coaxial threaded hole 52 for the reception of a threaded stud 53 carried by the pillar 14 which rotatably supports the motor housing 15.

In order to accommodate the upper ends of the struts 42, the annular supporting member 40 is necked-down to provide a peripheral shoulder against which the upper ends of the struts abut. The strut ends may be fixed to the member 40 conveniently by a welding operation.

It will be apparent upon reference to Fig. 7, that the lower ends of the struts 42 and the clamping collars 44 operate to grip fixed masts of various outer diameters in the same manner as the gripping collar 24 and upper ends of the struts 32 operate to grip various sizes of rotatable masts 12. The intermediate portions of the struts 42 are reinforced by ribs 54 and are joined to the end portions thereof by smooth double bends as at 55 which permit alteration of the angles thereof. Thus the lower ends of the struts 42 can readily be made to lie parallel to the mast axis regardless of the size of the mast so as to maintain the desired coaxial relationship.

Upon reference to Figs. 1 and 6, it will be seen that the intermediate portions of the struts 42 bridge the space between the lower end of the annular supporting member 40 and the upper end of the fixed mast portion 10. Thus they can be conveniently used for the support of auxiliary equipment such, for example, as a cable connector or junction box indicated generally at 66, the same being fastened in place by any suitable stirrup-like strap, mounting screws or the like.

It will be apparent from the foregoing that a supporting device fashioned in accordance with the present invention and including a rotatable mast supporting portion and a fixed mast supporting portion for mounting the same on the

fixed and rotatable elements of a rotary joint structure provides not only the rugged means required for joining the two mast sections together, but at the same time maintains them in coaxial relation regardless of the sizes of the mast sections employed. Gripping of the mast sections by means of the segmental collars and their bolt-and-nut fasteners makes use of the resilient character of the cylindrical tubing of which the mast sections are formed. As a result, actual contact between the segments of the gripping collar and the surfaces of the mast sections becomes a ribbon area contact as the mast sections are slightly deformed upon the tightening of fasteners. This eliminates any localized deformation of the mast sections which together with the rigid brace action of the struts insures against bending even if the antenna structure should be subjected to exceedingly severe winds.

I claim as my invention:

1. In an antenna rotator for interconnecting rotatable and nonrotatable antenna mast sections, the combination comprising, a cylindrical member, a generally bell-shaped housing coaxially and rotatably supported thereby, a plurality of downwardly extending struts having their upper ends secured to said member, a segmental clamping collar embracing said struts for clamping the latter against the nonrotatable mast section, an axial centering post extending upwardly from said housing for receiving the lower end of the rotatable mast section, a plurality of upper struts having their lower ends secured to the upper periphery of said housing and extending upwardly and inwardly on an incline therefrom, and a segmental clamping collar for clamping the upper ends of the upper struts against the rotatable mast section.
2. In an antenna rotator for supporting a tubular antenna mast, the combination comprising, a generally bell-shaped housing, means for rotatably supporting the housing, an axial upwardly tapering post for receiving the lower end of the mast, a segmental clamping band embracing said housing, a plurality of flat struts secured to said band and extending upwardly and inwardly on an incline therefrom, and an adjustable segmental collar embracing the upper ends of said struts for clamping the latter against the mast.
3. In an antenna rotator for connecting an antenna mast to a stationary mast, the combination comprising, a cylindrical member, means rotatably carried on said member for supporting the antenna mast, said member having an axial downwardly opening socket, a plurality of struts secured to the member and extending downwardly therefrom, said struts having transversely curved lower portions for engaging the stationary mast, and a pair of segmental clamping collars embracing said curved lower portions of said struts for clamping the latter against the stationary mast, said struts having flat portions between said collars and said member to provide for flexure of said struts to accommodate various sizes of stationary masts.

4. In an antenna rotator for interconnecting rotatable and non-rotatable antenna mast sections, the combination comprising, a cylindrical member, a generally bell-shaped housing coaxially and rotatably supported thereby, means for rigidly mounting said member at the top of said non-rotatable mast section and coaxial therewith, an axial centering post extending upwardly from said housing for receiving the low-

er end of the rotatable mast section, a plurality of upper struts having their lower ends secured to the upper periphery of said housing and extending upwardly and inwardly on an incline therefrom, and a segmental clamping means for clamping the upper ends of the upper struts against the rotatable mast section in symmetrically spaced relation.

5. In an antenna rotator for supporting a tubular antenna mast, the combination comprising, a generally bell-shaped housing, means for rotatably supporting the housing, an axial upwardly tapering post for receiving the lower end of the mast, a plurality of struts for coupling said housing and said tubular antenna mast, means for anchoring the lower ends of said struts rigidly to the periphery of said housing and symmetrically spaced thereabout so that the struts extend upwardly and inwardly therefrom, each of said struts providing a pair of radially extending ears at its upper end and with the ears on adjacent struts being arranged in pairs opposite one another, and means including a threaded bolt for engaging each pair of ears for drawing the ears clampingly toward one another.

6. In an antenna rotator for connecting an antenna mast to a stationary mast, the combination comprising, a cylindrical member, means

10
